(57) **CLAIM**

I claim the ornamental design for an axial blowing machine, as shown and described.

DESCRIPTION

FIG. 1 is a top view of the axial blowing machine;

FIG. 2 is a greatly enlarged back view of the axial blowing machine shown in FIG. 1;

FIG. 3 is a right side view of the axial blowing machine shown in FIG. 1;

FIG. 4 is a left side perspective view of the axial blowing machine shown in FIG. 1;

FIG. 5 is an enlarged right side perspective view of the axial blowing machine shown in FIG. 1; and,

FIG. 6 is a greatly enlarged front view of the axial blowing machine shown in FIG. 1.

Any surfaces of the design not shown, including interior surfaces, form no part of the claimed invention.
